(57) **CLAIM**

The ornamental design for a pharmaceutical waste container, as shown and described.

DESCRIPTION

FIG. 1 is a perspective view of a pharmaceutical waste container showing my new design, showing an insert member assembled on the pharmaceutical waste container, with the insert member having a tab and a cap each shown in an opened configuration;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right-side elevation view thereof;

FIG. 8 is another perspective view of the pharmaceutical waste container of FIG. 1, showing the insert member disassembled from the pharmaceutical waste container, with the tab of the insert member and the cap shown in an opened configuration;

FIG. 9 is another perspective view of the pharmaceutical waste container of FIG. 8, showing the insert member assembled on the pharmaceutical waste container, with the insert member having the tab shown in a closed configuration and with the cap shown in an opened configuration;

FIG. 10 is a top plan view thereof;

FIG. 11 is a bottom plan view thereof;

FIG. 12 is a front elevation view thereof;

FIG. 13 is a rear elevation view thereof;

FIG. 14 is a left side elevation view thereof;

FIG. 15 is a right-side elevation view thereof; and,

FIG. 16 is another perspective view of the pharmaceutical waste container of FIG. 9 shown in a closed configuration.
